LUGGAGE HARDWARE

David Levine, New York, N. Y., assignor to Crest Lock Co., Inc., New York, N. Y., a corporation of New York

Application October 21, 1948, Serial No. 55,671

2 Claims. (Cl. 190—58)

1

The present invention relates to an article of luggage hardware, more particularly to a piece or ring, generally known as a D ring, for connecting a luggage handle to the article of luggage proper. The term "luggage" as used herein embraces ladies' handbags.

In connecting a handle to many types of articles of luggage, a D ring is passed through a hole or loop at the end of the handle and through another loop in a strip of leather, or the like, generally formed by the folding over of the leather strip, which is secured to the luggage piece.

Heretofore, three different conventional types of D rings have been used in the art, each type with certain disadvantages inherent in its construction.

One type of D ring heretofore used is a split ring made of wire, its ends generally meeting along a straight side of the ring. Such ring requires to be first spread open, which is a separate, time consuming operation, requiring the use of tools. It then must be pushed through the loop in the handle; an operation requiring a great deal of manipulation, especially with stiffened handles. It next must be assembled with the loop of the folded connecting strip, an operation which again requires the use of tools, such as pliers or a hammer, to close the ring. Usually the ring cannot be restored to completely closed state and a gap remains which widens, in time, through repeated use, sufficiently for the ring to become disengaged from the connecting strip or handle.

Another type of D-ring conventionally used is a cast split ring. Such ring is delivered opened to the luggage manufacturer and does not require the spreading operation. However, such cast ring is necessarily of greater thickness and stiffer than a wire ring, so that the assembly with the handle becomes more difficult and the closing operation requires greater force and effort and frequently results in breakage during closing.

A third, conventional type of D ring heretofore in use is the one piece ring, which is either cast, forged or stamped. This type of D ring must be sent out by the luggage manufacturer to have the handle built around it, at considerable increased cost of the handle. Furthermore, the ring and handle must be assembled with the connecting strip and the connecting strip secured to the luggage piece before any of the pockets, partition and lining may be secured in place thereon. As a consequence, any delay in the delivery of the rings and handles from the handle maker will result in the stoppage and delay of the entire production, at enormous cost to the manufacturer.

The present invention contemplates, therefore, the provision of a D ring which possesses none of the disadvantages of any of the foregoing con-

2

ventional types of D-rings and which possesses all of their combined advantages.

It is an object of the present invention to provide a D-ring of the character described which does not require any bending or distortion of its shape to open or close for assembly purposes.

It is another object of the present invention to provide a D-ring of the character described which will not loosen and become disengaged from the connecting piece or handle during use.

It is also an object of the present invention to provide a D-ring of the character described which will permit the assembly of the handle with the luggage piece at any time, either before or after completion of the luggage piece proper and may not, therefore, interfere with or retard the production line.

It is still another object of the present invention to provide a D-ring of the character described which is strong and durable and is not likely to break during assembly.

It is still further an object of the present invention to provide a D-ring of the character described which is itself economical to produce and which may be used to connect a handle to a luggage piece with great facility, with a minimum of force and effort and a great saving in time and labor with resulting production economies.

The foregoing and other advantages and superiorities of the D-rings of the present invention will become more readily apparent to those skilled in the art from the several embodiments thereof shown in the accompanying drawings and from the description following. It is to be understood, however, that such embodiments are shown by way of illustration only, to make the principles and practice of the invention more readily comprehensible, and without any intention of limiting the invention to the specific details therein shown.

In the drawings:

Fig. 1 is a side elevation of a luggage piece employing a D-ring of the present invention to secure its handle thereto;

Fig. 2 is an end elevation of the same;

Fig. 3 is an enlarged fragmentary view of the D-ring, handle and connecting strip assembly, with the D-ring partly in section to show structural details thereof;

Fig. 4 is an edge view of the assembly of Fig. 3;

Fig. 5 is a section taken on line 5—5 of Fig. 3;

Fig. 6 is a view similar to Fig. 3, showing the assembly before the D-ring is completely closed;

Fig. 7 is a view similar to Fig. 3, showing a modified form of D-ring; and

Fig. 8 is an edge view of the assembly of Fig. 7.

Referring more specifically to the accompanying drawings, it will be seen that, generally stated, the D-ring of the invention which may be made of any suitable metal by any desirable

process comprises a substantially U-shaped section and an associated, separate pin or pintle section which spans the opening of the U-section.

In the embodiment of Figs. 1-6, inclusive, the U-shaped section, generally designated as 10, comprises an arcuate base portion 11 and side portions or legs 12 and 13 substantially parallel to one another. The legs 12 and 13 are each provided adjacent their ends, with an aperture, such as 14 and 15, respectively, which are aligned and facing one another. One of the apertures, such as 14, may be of uniform cross section throughout and may extend completely through the leg 12, or it may extend only partly therethrough, just forming a recess therein, as illustrated. The other aperture 15 may have at least its outer portion of enlarged cross section, to form a seat or socket 16.

The opening of the U-shaped section 10 is spanned and closed by a loop engaging pin or pintle 17, which may be inserted through the aperture 15 and into the aperture 14, to bridge the opening of the section 10. The pintle 17 is formed with an enlarged, finely knurled head 18 at one end, of a cross section slightly larger than the cross section of the socket 16 so that it may be force-fitted into the socket to be thereby tightly and safely secured in place. The other end of the pintle may be snugly fitted without force into the aperture 14.

In use, a strip 20 is secured in suitable location on the bag 21 as by stitching or other suitable means, and preferably in folded over position, to form a detached loop 22. The section 10 of a D-ring of the present invention is then inserted through an opening or loop 23 at the end of a preformed handle 24. The pintle 17 is then inserted through the aperture 15 through a loop 22 and into the aperture 14 and is secured in place by having its knurled head 18 force-fitted, by means of suitable tool or device into the socket 16.

It will be readily apparent that the section 10, not having any inwardly bent end portions such as found in the conventional split wire ring, may be easily and rapidly inserted through the openings 23 of the handle 24, and that the D-ring of the present invention may be engaged with the connecting strip 20 with equal ease and speed, without any danger of breaking and at any time prior to or after the luggage piece 21 has been otherwise completed.

It also will be apparent that a small and simple tool can be employed to force fit the pintle in its operative position.

In the embodiment of Figs. 7 and 8, the U-shaped section, generally designated as 30, may be formed with a straight base portion 31 which may have the legs 32 and 33 extending to one side thereof and the internally formed closed loop or ring 35 extending to the other side thereof, such closed loop being provided, preferably, with a straight loop-engaging side 36 substantially parallel to the base portion 31.

In practice, the D-ring of Figs. 7 and 8, is first secured to the strip 20 by passing the fold of the strip 20 over the side 36 of the closed ring section 35 before it is secured to the luggage piece 21. The D-ring is then secured to the handle 24 by passing the pintle 17 through the 70 end loop 23, thereof, and securing the head 18, by force fitting, into the socket 16.

This completes the description of the several embodiments of the D-rings of the present invention. It will be apparent, however, that many 75

modifications and variations of the same may be made by any one skilled in the art, in accordance with the principles of the invention hereinabove set forth and without the use of any inventive ingenuity.

I desire, therefore, to have the protection of the patent laws for any and all such modifications and variations that may be made within the spirit of the present invention and the scope of the claims hereto appended.

What I claim is:

1. A ring for connecting a preformed loop of a piece of luggage to a preformed loop of a handle, said ring comprising a U-shaped member including a base and substantially parallel widely spaced legs, said ring additionally comprising a pintle, one end of said pintle being larger than the other, said legs having aligned facing apertures formed therein, the opposite ends of said pintle being received in said apertures, the aperture which receives the larger end of the pintle being a through aperture and having a diameter slightly smaller than the diameter of said larger end, the other aperture 20 slidably receiving the smaller end of the pintle, whereby with the base of the U-shaped member in one of the preformed loops, the smaller end of the pintle can be threaded first through the through aperture and then through the other preformed loop after which said small end is slidably received in its aperture as the larger end is force-fitted in the through aperture.

2. A ring for connecting a preformed loop of a piece of luggage to a preformed loop of a handle, said ring comprising a U-shaped member including a base, a pair of substantially parallel widely spaced legs and a bar in one piece with said legs and extending therebetween intermediate the opposite ends of the legs so that the bar 35 is spaced from the base and from the tips of the legs, said ring additionally comprising a pintle, one end of said pintle being larger than the other, said legs having aligned facing apertures formed therein, the opposite ends of said pintle being received in said apertures, the aperture which receives the larger end of the pintle being a through aperture and having a diameter slightly smaller than the diameter of said larger end, the other aperture 40 slidably receiving the smaller end of the pintle, whereby with the base of the U-shaped member in one of the preformed loops, the smaller end of the pintle can be threaded first through the through aperture and then through the other preformed loop after which 45 said small end is slidably received in its aperture as the larger end is force-fitted in the through aperture.
